UNITED STATES PATENT OFFICE

156,199

DESIGN FOR AN AUTOMOBILE SEAT

Robert Cadwallader, Detroit, Mich., assignor to
Kaiser-Frazer Corporation, Willow Run, Mich.,
a corporation of Nevada

Application January 21, 1948, Serial No. 143,947

Term of patent 14 years

(Cl. D14—6)

To all whom it may concern:

Be it known that I, Robert Cadwallader, a citizen of the United States of America, residing at Detroit, in the county of Wayne, State of Michigan, have invented a new, original, and ornamental Design for Automobile Seats, of which the following is a specification, reference being had to the accompanying drawing forming a part thereof.

In the drawing:

Figure 1 is a front, elevational view of an automobile seat showing my new design and showing a center arm rest in its down or extended position;

Fig. 2 is a perspective view of the seat shown in Fig. 1;

Fig. 3 is a side elevational view of the seat shown in Fig. 1; and

Fig. 4 is a view similar to Fig. 1 but showing the center arm rest in its closed or raised position.

The back of the seat is not ornamented.

I claim:

The ornamental design for an automobile seat, as shown and described.

ROBERT CADWALLADER.
